(57) **CLAIM**

The ornamental design for a push-button release latch, as shown and described.

DESCRIPTION

FIG. 1 is a perspective view of a push-button release latch showing my new design thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view; and,

FIG. 8 is a perspective view thereof, with the push-button release latch shown in closed position and its environmental use.

The broken line environment is for illustrative purpose only and forms no part of the claimed design.
